[57] ABSTRACT

When a trench is to be dig for the purpose of laying pipe, cable, or tubing, the cutting mechanism includes a blade which is vibrated vertically by a suitable driving means, and which can also be adjusted horizontally to provide space through which the trenching mechanism may be moved so that it is possible to use either the trenching machine alone or the plow mechanism alone, or the use of both mechanisms simultaneously if required.

FIG.5

OSCILLATING PLOW AND TRENCHER COMBINATION

An object of my invention is to provide a vibrating plow which can be adjusted horizontally to various positions rearwardly of the mobile tractor, and can also be moved vertically to engage the ground and form a slit trench therein.

Another object of my invention is to provide a novel trenching mechanism with the vibrating plow so that the trenching mechanism may be moved between the rear of the mobile mechanism and the plow to permit the trenching machine to operate either simultaneously with or independently of the plow.

Another object of my invention is to provide a combination vibrating plow and trencher in which the trenching mechanism can function to dig a trench ahead of the plow so that both the trenching mechanism and the plow can be used simultaneously.

Other objects, advantages and features of invention may appear from the accompanying drawings, the subjoined detailed description and the appended claims.

In the drawings:

FIG. 1 is a side elevation of my combination vibrating plow and trencher showing the trenching mechanism in raised or traveling position.

FIG. 2 is a top plan view of the mechanism.

FIG. 3 is a sectional view taken on line 3—3 of FIG. 2.

FIG. 4 is a side elevation of my combination plow and trenching mechanism showing the trencher in various positions between traveling and digging.

FIG. 5 is a plan view of FIG. 4.

Referring more particularly to the drawing, the plow mechanism 1 is mounted on the mobile vehicle 2 or the frame of that vehicle. The mount for the plow mechanism 1 consists of a pair of spaced tubes 3 and 4 which are spaced horizontally and serve to secure the plow to the tractor. Each of the mounts 3 and 4 carries slidable sleeves 5 and 6, respectively, which thus rigidly support the plow mechanism 1.

The plow mechanism 1 includes a frame 7, which frame is pivotally attached to the sleeves 4 and 5 by suitable pivot bolts 8. It is obvious that the plow frame 7 can be swung around the pivots 8 by means of hydraulic cylinders 9 extending between the sleeves 5 and the frame 7.

The plow 10 is oscillated or vibrated by the mechanism 11 of the type shown in my U.S. Pat. No. 3,563,045, Feb. 16, 1971.

The entire frame 7, together with the plow 10 and its vibrating mechanism 11, can be moved horizontally by sliding the sleeves 5 and 6 along the tubes 3 and 4. This

is accomplished by the hydraulic cylinders 12-13, which cylinders are attached at one end to the frame of the mobile vehicle 2 and at the other end to the frame 7. Thus by motivating the pistons 12-13 it is possible to move the entire plow mechanism from the position shown in solid lines in FIG. 1 to the position shown in dotted lines in that same figure. Thus the plow mechanism can be moved horizontally either towards or away from the mobile vehicle 2.

10 A trenching mechanism 14 is also mounted on the vehicle 2 between the sleeves 5 and 6. The trencher 14 consists of an endless belt or chain 15 which is driven by a suitable motor 16 of the usual and well known type. The trencher 14 can be pivoted around the drive of the motor 16 to move the trencher to various positions shown in FIG. 4, either to a raised or traveling position or a lowered or digging position. The belt or chain 15 can move between the mounting sleeves 5-6 of the plow or it can be swung entirely to a lowered position when the plow is moved rearwardly to the dotted position shown in FIG. 1. The trencher 14 can be raised or lowered by means of the hydraulic cylinder 17.

Having described my invention, I claim:

25 1. An oscillating plow and trencher combination comprising a frame extending from a pulling vehicle, a pair of mounting tubes secured to said frame, a sleeve slidably mounted on each said tube, a plow pivotally mounted on said sleeves, oscillating drive means for said plow, an endless trenching mechanism, means pivotally mounting the trenching mechanism on said frame between said sleeves and tubes, and power means connected to the trenching mechanism to pivot said mechanism around said pivotal mounting means.

2. An oscillating plow and trencher as recited in claim 1, and power means engaging said sleeves to move said plow horizontally.

3. An oscillating plow and trencher as recited in claim 1, said trenching mechanism being positioned between the plow and the pulling vehicle.

4. An oscillating plow and trencher as recited in claim 1, power means engaging said sleeves to move said plow horizontally, said trenching mechanism being positioned between the plow and the pulling vehicle.

5. An oscillating plow and trencher as recited in claim 1, and a hydraulic cylinder engaging each said sleeve to move the same on said tubes.

6. An oscillating plow and trencher as recited in claim 1, and power means engaging said sleeves to move said plow horizontally, said power means comprising a hydraulic cylinder engaging each said sleeve.
